LEVERAGE PULLEY

Anders R. Lofstrand, Silver Spring, Md.

Original application August 19, 1943, Serial No. 499,271. Divided and this application August 14, 1946, Serial No. 690,504

4 Claims. (Cl. 74—517)

1

This invention relates to winding drums and the like and is a division of my present application, Number 499,271, filed August 19, 1943, for Glassware washing machines.

In a glassware washing machine as set forth in my above-mentioned prior application, there is provided an elevator for raising and lowering the glassware into and from a washing tub. The weight of the elevator is balanced or compensated by a spring which is fixed on to the machine and the elevator is connected to the spring by a cable or cord trained over a pulley in such a manner that as the elevator is lowered a compression force is exerted on the spring tending to return the elevator to its raised or original position. By using a conventional pulley for the cable, the force applied to the spring and consequent return force applied to the cable would increase proportionately with the travel of the elevator, so that by the time the elevator had reached the lowest limit of its travel a very great return force would be applied and it would require much strength to hold the elevator in this position.

The most desirable condition in an elevator of this kind would be to have a constant return force applied to the elevator. It is realized that such a constant force may be applied by the use of a compensating weight in place of the spring, but the disadvantages of using such a weight do not justify its use, for the weight is much more awkward to handle and requires more room in which to operate than a spring structure. By using a lever pulley so designed as to permit the cable to be trained over it and that more cable leaves the pulley on the elevator side than comes onto the pulley on the spring side and that the amount of cable leaving the pulley increases with rotation thereof while the amount going on remains constant, the advantages of both the spring compensating means and the weight balancing means are utilized and their disadvantages are minimized.

It is, therefore, an object of this invention to provide a leverage pulley of the kind hereinafter described, whereby the increase of return spring force on the compensating spring will vary in inverse relation to the travel of the elevator so as to provide a substantially constant return force on the elevator.

Another object of this invention is to provide a spiral pulley or plate which may be used with a conventional symmetrical pulley to achieve the result as set forth above.

Still another object of this invention is to

2

provide a spiral pulley or plate which may be mounted adjacent to a conventional circular pulley and a transfer or adapter plate for training the cord from the circular to the spiral pulley for the purpose as herein set forth.

With the above and other objects in view, my invention consists in the arrangement, combination and details of construction disclosed in the drawings and specification, and then more particularly pointed out in the appended claims.

In the drawings, wherein similar reference characters designate similar parts throughout the respective views,

Figure 1 is a side elevation of a leverage pulley constructed according to an embodiment of my invention.

Figure 2 is an end view seen from the right of Figure 1.

Figure 3 is a vertical section taken on the line 20 3—3 of Figure 1.

Figure 4 is a vertical section taken on the line 4—4 of Figure 1.

Referring to the drawings, the numeral 10 designates generally a leverage pulley constructed according to an embodiment of this invention, particularly adapted for use with the glassware washing machine as set forth in my copending application as set forth above.

The leverage pulley 10 comprises a plate 11, an annular pulley 12, and a transfer block 14. The plate 11 is formed of a flat plate of a substantially spiral configuration, the spiral outline extending approximately three hundred and sixty degrees around a bushing 15. The plate 11 between the extremities of the periphery thereof is formed with a cut-out or recess 16 providing a reduced part 17 at the outermost end of the spiral plate 11. The plate 11 has a groove 18 about the outer edge thereof which terminates at the inner portion of the reduced part 17. The plate 11 is further formed on one side with an opening 19 therethrough above the inner end of the recess 16 and oppositely inclined grooves 20 and 21 extending from the opening 19 to the outer end of the recess 16. A groove 22 on the other side extends from the opening 19.

An annular grooved pulley 12 is disposed in face abutting relation to the spiral pulley 11 and is secured on a cylindrical bushing 15 which extends through both pulleys 11 and 12.

An arcuate block 14 is secured to the pulley 11 by fastening members 24 and is formed with a groove 25 on the outer edge thereof in which a cable 26 is adapted to be engaged.

In the use of this pulley 10, the cable 26 is

brought upwardly over a part of the annular pulley 12, reverted onto the block 14, through groove 22, hole 19, grooves 20 and 21, and is reverted again over the arm 17 and through the groove 18 about plate 11, thence downwardly to the elevator. In this manner the movement down of the elevator will cause the pulley 10 to rotate clockwise, increasing the lever arm on the elevator side, thereby providing for an increase in elevator downward travel upon rotation of the pulley 10 while the increase of spring tension on the other end of the cable 26 remains constant.

I do not mean to confine myself to the exact details of construction herein disclosed but claim all variations falling within the purview of the appended claims.

Having thus described my invention, what I claim is:

1. A leverage pulley comprising a plate of substantially spiral configuration having a groove in the outer edge thereof, an annular grooved pulley secured to one face of said plate, and a block secured to said plate and formed with a longitudinally curved grooved outer edge, said plate having an opening therethrough whereby a cable may be extended from the grooved outer edge of said block through said opening and into the groove of said plate.

2. A leverage pulley comprising a plate of substantially spiral configuration having a groove in the outer edge thereof, an annular grooved pulley on one side of said plate, a bushing securing said plate and annular pulley together, a block having an inner edge substantially contacting with an edge of said pulley, and means securing said block to said plate, said block having a grooved longitudinally curved outer edge, said plate hav-

ing an opening therethrough adjacent one end of said block whereby a cable may be trained partially about said annular pulley underneath said block, over the groove in said block, through said opening and then trained in the groove of said plate starting from said lever arm.

3. A leverage pulley comprising a plate of substantially spiral configuration, having a groove in the outer edge thereof, said plate being formed with a cut-out between the extremities of said groove, and an opening on one side thereof, said plate being formed with a second groove communicating between said opening and said cut-out, an annular grooved pulley secured to one face of said plate, and a grooved block secured to said plate adjacent said annular pulley for training a cable from said annular pulley into said spiral plate.

4. A leverage pulley comprising a plate of substantially spiral configuration formed with a groove in the periphery thereof, an annular pulley adjacent one face of said plate, a common axis of rotation for said plate and said pulley, said plate formed with an opening therethrough whereby a cable may be extended from the grooved outer edge of said plate through said opening into the groove of said pulley.

ANDERS R. LOFSTRAND.
